Inventor.

Thomas Haynes

United States Patent Office.

THOMAS HAYNES, OF ST. LOUIS, MISSOURI.

Letters Patent No. 69,993, dated October 22, 1867.

IMPROVED KNIFE-SHARPENER.

The Schedule referred to in these Letters Patent and making part of the same.

Be it known that I, THOMAS HAYNES, of the city and county of St. Louis, State of Missouri, have invented a new and useful machine for Sharpening Knives, Scissors, and other articles of cutlery; and I do hereby declare that the following is a true, full, clear, and exact description of the construction and operation of the same, reference being had to the annexed drawings, making a part of this specification, in which—

Figure 1 is a perspective view.

Figure 2 is a lateral section.

Letters A and B, fig. 1, are perpendicular columns, firmly secured to or cast with the broad base C. D, E, and F are quadrangular transverse bars, severally supported by the columns A and B. G, H, and I are thumb-screws penetrating in the columns A and B to the apertures made to receive the ends of bars D, E, and F. K, L, and M, fig. 2, are the ends of the transverse bars D, E, and F, and are supported by columns A and B. N is a slot in the columns A and B. P is the handle to transverse bar D. O is a pivot, upon which the end of bar D turns, and Q Q are clamps, with aperture for screws.

To enable others to make and use the machine, I will proceed to describe its construction and operation.

The columns A B, the base C, and also the transverse bars D and F may be made of iron or other metal. The middle bar E should be made of hardened steel. The manner of construction is as follows:

The columns should be made so as to admit the arrangement of the three transverse bars D, E, and F, as follows, viz: The end of the bar D, fig. 1, rests within the slot N, fig. 2, and is secured by and works upon the pivot O, fig. 1. The other end of said bar D passes through slot N, fig. 1, in column A, and terminates in the handle P. By means of this handle the end of bar D, to which it belongs and is a part, can be elevated or depressed at pleasure, and then secured in the desired position by the thumb-screw G. The bar E rests upon the columns A and B, and can be placed in position or removed at pleasure, by passing it through an aperture corresponding in size, as shown by letter L in fig. 2. This bar may be firmly secured by thumb-screw H. When in position its angular edges are parallel with, and in close proximity with, the upper and lower bars D and F. Said bar E may be constructed in a triangular, quadrangular, sexangular, octagonal, or any other angular form, and placed so that one of its angular edges may be used. The lower bar F, fig. 1, is also supported by columns A and B. The end resting in column B is in a slot, so that it can be elevated or depressed and secured in the position desired by thumb-screw I.

The manner in which the machine is operated is as follows: The knife or other article to be sharpened is passed between the bars D E or F E; the edge of the knife or blade is pressed upon the angular edge of the middle bar E, whilst the edge of the back at the same presses upon the bars D or F. The space between the bars D and E and F and E may be lessened or enlarged at pleasure by means of the thumb-screws G and I. The knife or other article to be sharpened is then drawn backwards and forwards, and its edge is soon evenly sharpened by contact with the hard angular edges of the bar E.

What I claim, as my invention, is—

The arrangement and application of the angular steel bar E, in connection with the bars D and F, in the manner hereinbefore described, for the purpose herein set forth.

THOMAS HAYNES.
